UNITED STATES PATENT OFFICE.

WILLIAM F. SCHWEIGER AND BENNETT D. STRAIGHT, OF ROCHESTER, NEW YORK,
ASSIGNORS, BY DIRECT AND MESNE ASSIGNMENTS, TO MULTIPOST COMPANY, OF
ROCHESTER, NEW YORK, A CORPORATION OF NEW YORK.

STAMP-AFFIXER.

1,012,021.

Specification of Letters Patent. Patented Dec. 19, 1911.

Application filed June 8, 1910. Serial No. 565,167.

To all whom it may concern:

Be it known that we, WILLIAM F. SCHWEIGER and BENNETT D. STRAIGHT, of Rochester, in the county of Monroe and State of New York, have invented certain new and useful Improvements in Stamp-Affixers; and we do hereby declare the following to be a full, clear, and exact description of the same, reference being had to the accompanying drawings, forming a part of the specification, and to the reference-numerals marked thereon.

Our present invention relates to machines for affixing postage stamps or labels, and it has for its object to provide a portable machine adapted for hand use, in which a strip of stamps may be inserted and successively discharged therefrom and affixed to the article to which they are to be applied.

20 A further object of the invention is to provide a suitable feeding mechanism for advancing the stamp strip step by step and devices operated conjointly therewith for depositing liquid on the article to which the stamp is to be applied before the stamp is affixed thereto.

Another object of the invention is to provide an arrangement of parts whereby the affixing member and the stamp feeding devices may be both locked in inoperative positions when the machine is not in use to prevent the unauthorized removal of the stamps, such locking of the parts being normally rendered inaccessible by the stamp holder itself, which is normally locked against removal.

To these and other ends the invention consists in certain improvements and combinations of parts all as will be hereinafter more fully described, the novel features being pointed out in the claims at the end of the specification.

In the drawings: Figure 1 is a side elevation of a machine constructed in accordance with our invention; Figs. 2 and 3 are vertical sectional views showing the parts in different positions; Fig. 4 is a similar view showing the affixing member and feeding mechanism locked in inoperative position; Fig. 5 is a detail view partly in section illustrating the disengaging of the carriage from the affixing member and the severance of the stamp strip by the latter; Fig. 6 is a top plan view of the machine; Fig. 7 is a

detail view of the stamp holder and its guide way, said parts being removed from the machine; Fig. 8 is a similar detail view of the interior of the machine with the stamp holder removed, showing the stamp feeding finger; Fig. 9 is a horizontal view taken on the line 9^x—9^x of Fig. 5; Fig. 10 is a similar view taken on the line 10^x—10^x of Fig. 5; Fig. 11 is a diagrammatic view illustrating the warping of a stamp strip as it is projected from the guide.

65

Similar reference numerals in the several figures indicate similar parts.

In illustrating one embodiment of our invention we have shown a machine having a frame composed of side pieces 1, connected at their bottom edges to a base plate 2, and at their rear edges by the wall 4, which also forms the top of the frame, and is provided with an aperture arranged centrally to an aperture in the base 2, through which the affixing member projects at certain times. The stamp affixing member reciprocates vertically in the frame and comprises the shaft 5 and the head or plunger 6 attached at its lower end, its upper extremity being provided with an operating knob or handle 7. Extending transversely through the lower end of the shaft is a rod or pin 8 the extremities of which are guided in parallel slots 9 formed in the side pieces 1 of the frame, 80 said pins also being provided with shoulders 10 engaging the proximate faces of the side pieces of the frame and serving to hold the affixing member centrally therein. Coil springs 15 are disposed at opposite sides of 90 the shaft 5 and are connected at their opposite extremities to eyes on the frame and plunger 6 for retracting the latter in the position shown in Fig. 2. At the forward side of the plunger is arranged the stamp container with its guide way by means of which the stamps are introduced into proper position in front of the plunger or affixing member. The stamps or labels are provided in a strip which is rolled as indicated by 16, 100 and the container in which they are held is preferably constructed in the form of a ring 17, fitted between the ears or extensions 18 on the sides of the frame, which are preferably perforated as indicated in Fig. 105 1, so that the operator may readily determine the quantity of stamps contained therein. At its lower side the ring is provided

with an opening or slit 19 through which the stamp strip passes into the downwardly extending guide way, the discharge end thereof being located near the base 2 abutting the bar or cutter 20 rigidly supported on the frame and which cooperates with the shearing edge 21 on the plunger 6. The guide way is embraced between the walls 22, which are connected at their outer and lower edges by the wall 23 to form a casing which is spaced apart from the guide way to accommodate suitable locking devices comprising a bolt 24 engaging an aperture in the base 2, for preventing the removal of the stamp holder. The latter is also retained by the hooks 25 on the ring 17 engaging an interior shoulder 30 on the top of the frame.

Arranged at the opposite or rear side of the affixing member is a receptacle or chamber 31 adapted to contain liquid, such as water, in the event the stamps or labels are gummed, although an adhesive substance such as mucilage might be employed therein. In the inner wall of the chamber at its lower end is provided an orifice, or a plurality of orifices, 32 adapted to direct the liquid discharged from the chamber across the path of the plunger 6 at a point beneath the open end of the stamp guide, so that a spray will be deposited on the article to which the stamp is to be affixed before the latter is severed from the strip. The means for ejecting liquid through the orifices comprises a piston 33, reciprocating horizontally in a chamber 34 and connected to a piston rod 35 guided in the walls of said chamber which are provided with perforations 36 preventing free ingress of the liquid thereto, but offering sufficient resistance to its displacement during the movement of the piston, so that the latter will cause a portion thereof to be ejected through the discharge orifices 32. The face of the piston is provided with a strip of packing 37 which normally closes the inner ends of the orifices and prevents leakage therethrough. A leaf spring 38 is connected to the outer end of the piston 35, and is attached at its upper end, as indicated at 39, to the top of the receptacle 31, and about midway of its length the spring is provided with an incline cam surface 40, which is disposed centrally of the spring and directly above the piston rod 35. A latch connection is formed between the affixing member and the spring by providing in the head 6 a pawl 41 pivoted in a recess and having an end 42 which prevents its movement in one direction, said pawl being normally held in the operative position by a leaf spring 43, as shown in Fig. 3. From this arrangement of the parts it will be seen that during the downward movement of the plunger the pawl 41 rides over the incline 40 and compresses the spring 38, and as it disengages the cam surface

allows the spring to impart a sudden movement to the piston 33, and upon the return movement of the affixing member the pawl will rotate on its pivot and thus pass the projection 40 without actuating the spring 38. The cam 40 is located in such a position that the movement of the piston 33 occurs in timed relation to the feeding and severing of the stamp, its release occurring just previous to the cutting off of a stamp. A suitable filling aperture is provided in the rear wall of the receptacle near its upper end which is normally closed by a screw plug 46 accessible through an aperture provided in the rear wall 4 of the frame.

The mechanism employed for feeding the stamp strip is designed to advance the latter step by step to project a single stamp across the cutter 20 into the path of the affixing member upon each reciprocation of the latter. This mechanism comprises a reciprocatory carriage provided with a finger or fingers projecting into the stamp way and cooperating with the stamp strip. Movement is imparted to the carriage to cause it to travel the distance required to properly feed the stamp during the movement of the affixing member in one direction, by means of a locking device securing these parts together which is automatically tripped to release the carriage when its required movement has been effected. The locking device mentioned is also intended to perform another function, that of locking the feeding mechanism in inoperative position and also holding the affixing member in its projected position, closing the aperture in the base and effectually preventing access to the stamps. In carrying out these features of the invention we preferably form the shaft 5 rectangular in cross-section and make the carriage of the feeding mechanism in the form of a sleeve 47, which is independently movable on the shaft 5, but prevented from rotary movement thereon by the shape of the parts. At the forward side of the carriage are projecting wings 48 between which is pivotally supported, on the rod 49, a latch member 50, provided with the hook end 52, which is normally pressed toward the adjacent side of the shaft 5 by a spring 53, supported by having its coils 54 wrapped around the ends of the pin 49. The end 52 of the latch member forms a pawl which is adapted to engage a shallow notch or recess 55 in the side of the shaft 5 near the lower end thereof and adjacent the plunger or head 6, and at certain times, as will be further described, the pawl also engages another notch 60. The upward movement of the carriage 47 is limited by the stop or projection 61 thereon engaging the top of the frame, to which position it is carried by the upward movement of the affixing member when it is retracted by the coil springs 130

51, in which position the notch 55 alines with the pawl 52, so that upon the downward movement of the affixing member the carriage travels therewith.

5 It is important in a machine of this character that the stamp strip be fed an exact distance, according to the length of the stamps or labels printed on the strip, so that the severance of the strip occurring upon 10 the downward movement of the affixing member will occur each time between successive stamps. Any inaccuracy in feeding the strip necessitates adjusting it in reference to the feeding device, and thus justifying 15 of the strip will be frequently required to prevent cutting off pieces of unequal length, a circumstance which is particularly undesirable when the machine is employed for affixing postage stamps.

20 The stamp feeding mechanism further comprises a finger 62 on the carriage 47, which projects into the stamp way and cooperates with the stamp strip therein during the downward movement of the affixing member. The finger 62 is preferably composed of a plurality of thin blades arranged side by side, as shown in Fig. 8, which are strung on a pin 63 supported between the wings 48 of the carriage, said pin being arranged at one corner of the blades so that the ends of the latter form shoulders 64 which coöperate with a resilient block of rubber or other suitable material 65. The latter is compressed between said ends of 25 the fingers and an overhanging cap piece 70 extending between the wings 48. By employing a resilient block 65 in the place indicated an independent movement is permitted to each of the plates, composing the finger 62, permitting these blades to automatically adjust themselves to any irregularity of the stamp strip, and permitting certain blades to move into engagement with the shoulders, formed by the perforations in the 30 stamp strip, whenever the feeding finger is moved along the surface of the latter. All of the fingers being yieldingly supported some of them will always engage in the perforations irrespective of the position of the perforations in the strip, or of the exactness with which said strip may be centered in the guide. The exact distance through 35 which the feeding mechanism is moved to control the projection of the stamp strip from the guide is determined by a strip or stop 71, stationary on the frame of the machine and adapted to coöperate with the cam surface 72 of a releasing finger 73 connected to the locking device or pawl 50, and for convenience in construction this tripping device or stop may be made as part of the cutter 20.

As before explained the carriage 47 when in its uppermost or inoperative position is arrested by the stop 61 engaging the top of

the frame of the machine, and when the affixing member is retracted by the coil springs 15 the pawl 52 is actuated by the spring 53 into engagement with the notch or recess 55 in the shaft 5. Now upon the downward movement of this shaft, the carriage 47 being locked to it is carried downwardly and during its downward movement some of the component elements of the feeding finger 62 engage the perforations in the stamp strip, and cause the latter to be moved downwardly in the guide way until the pawl 52 is tripped by the engagement of the cam surface 72 with the stop 71, as shown in Fig. 5. This releasing of the carriage from the affixing member occurs just previous to the engagement of the shear 21, on the head 6, with its coöperating cutter 20, consequently the movement of the feeding mechanism is arrested after the stamp strip has been projected the required distance, and the cutting off of the stamp is effected by the continued movement of the affixing member, the head 6 of which after passing the cutter 20 projects through the aperture in the base 2 of the frame into engagement with the article to which the stamp is to be applied. When the operator releases the knob 7 the shaft 5 in moving upwardly carries with it the sleeve 47, the upward movement of which is first arrested while the shaft 5 is permitted to move therethrough until its limit of movement is reached and the locking member 52 is again permitted to automatically engage the aperture 55.

It will thus be seen that the successive operations of feeding and affixing the stamps may be continued until the supply of stamps is exhausted. When, however, it is desired to lock the machine to prevent the surreptitious or unauthorized removal of a stamp the operator will be careful not to allow the affixing member to be retracted into its inoperative position after the last stamp desired has been discharged from the machine. At such time the shaft 5 is allowed to retract only a sufficient distance to cause the spring-tongue or finger 74 to project through the slot or aperture 75 in the top of the frame where it may be grasped by the operator to retain the carriage in its uppermost position while the affixing member is again projected into its lowermost position, as shown in Fig. 4, when the pawl 52 will engage the notch or recess 60. For convenience in holding the carriage in inoperative position temporarily the spring finger 74 is undercut at its edges, as indicated at 76 in Fig. 8, forming a narrow portion which may be deflected into a corresponding recess 77 arranged at one side of the aperture 75, as shown in Fig. 6. The affixing member, when locked in the position just described is in projected position its further movement in this direction being

limited by the engagement of the pins 8 with the lower ends of the guide slots 9 of the frame. The carriage 47 being also limited in its movement in the opposite direction by abutting against the wall of the frame, and being firmly locked to the shaft effectually prevents any movement of the affixing member which would permit access to the stamps in the guide way. The location of the stamp holder and its guide way at the front of the frame, so that it normally renders the locking device inaccessible, will be seen to be a particularly advantageous arrangement of the parts as it is necessary to displace the holder and its guide way before the affixing member can be released for further operation, and these parts being locked the machine can only be released by the proper authority.

In a machine of this character it is also desirable to prevent the removal of the stamps when the affixing member is not locked, as described above, and during the time it is in actual use, and to this end we have provided a particular arrangement of elements whereby any attempt to extract stamps by drawing the strip forwardly from the discharge end of the guide way will be thwarted and result in rendering the machine inoperative. In carrying out this feature of our invention the guideway is provided with a portion which is adapted to impart a curve to the stamp strip as the latter is projected or advanced lengthwise therein so that in the event the strip is pulled at its free end, in contradistinction to its being pushed forwardly by the feeding devices, it will be pulled out of its normal path or deflected and thus become bound in the guideway to prevent the strip from being fed further. The guideway also includes a yielding part or tensioning means which cooperates with the stamp strip to cause it to follow continuously the normal curve imparted to it but which will move when a strain is exerted on the free end of the strip. The deflecting of the strip in the guideway occasioned in this manner is sufficient to draw it into engagement with an arresting member which is so positioned relatively to the guideway that as the stamp strip traverses its normal path while being pushed ahead by the feeding mechanism, said strip will freely pass around one side of said arresting member. In the arrangement of the parts illustrating the present embodiment of the invention the guide way is arranged to project downwardly from the stamp holder in a direction parallel to the direction of movement of the affixing member and the feeding mechanism, and the position for imparting the curve to the stamp strip is located at the lower end of the guideway where it is curved laterally to the point of discharge at the cutting bar. The

back of the guide way is a stationary plate 78 receiving the thrust of the feeding finger 62 and the front of the guide way is composed of a frame 79 having an open center which is supported at a central point on 79 yielding fingers 80 attached at their upper ends to the ring or stamp holder 17. The lower end of the frame 79 forming the inner curved surface of the guide way rides lightly upon the stamp strip passing therethrough, 75 and since it is held at its center by the spring fingers 80, its lower end will be moved away from the stationary part 78 of the guide if the stamp strip is displaced relatively thereto, as will occur in the event the stamp strip is pulled forwardly. The movement thus imparted to the lower end of the frame 79 will cause its upper end 81 to be tilted to bind the stamp strip in the guide way at its upper or entrance end. Another 85 means is also employed for further arresting the stamp strip comprising a projection or series of projections such as needles 82, mounted on a transversely extending bar 83, which are arranged with their pointed ends 90 in juxtaposition to the stamp strip and in such a position that the latter when displaced by an attempt to draw it forwardly in the guide will either puncture the paper or pass through the perforations therein. 95 The spring frame 79 is held in position by the light spring tension of the fingers 80 and the frame resting lightly against the stamp strip constitutes a tensioning device which performs the function of holding the 100 stamp strip in place. A pull on the extremity of the stamp strip which imparts a non-functional tension thereto will vary the normal tension of the strip and may be less than that required to tear off the outermost 105 stamp, even if the strip is perforated, and still be sufficient to deflect the intermediate portion of the strip lying in the guideway into engagement with the arresting members or needles 82. The strip becoming thus 110 impaled on the needles is held by them in its deflected position effectually preventing the further feeding of the stamps until the stamp holder is detached from the machine and the stamp strip restored to its normal 115 position.

The strips of stamps are preferably wound into a roll and when retained in this condition the strip when unrolled still possesses a tendency to curl, thus giving to each 120 stamp a slight curve, and in addition to this the discharge of the strip from the curved extremity of the guide way will impart the same tendency thereto, as indicated in dotted lines in Fig. 11. This sometimes 125 causes the stamp to curl at its edges after it has been applied to an article, or to curl in such a manner that more or less of one edge of a stamp will be turned back or folded upon itself when engaged by the 130

affixing member and to overcome these difficulties and also to facilitate the severance of the stamps from the strips we have provided means for warping or curving the stamps transversely of the strip. This we do by causing the end of the strip to be rounded slightly at its center, after it has passed the curve of the guide way and as it emerges from the open end or throat. This curving of the strip transversely flattens the stamp and entirely overcomes the inherent tendency of the paper to curl from other causes. To accomplish this we provide the discharge end or throat of the guide way with a warping surface 84 which is formed by raising the center of the guide way above its edges, so that the strip as it is fed thereover will be raised at the center sufficiently to cause the stamps projected therefrom to be held in horizontal alinement with the end of the guide way. The edge of the cutter 20 is similarly shaped, as shown in Fig. 8, so that when the straight cutting edge 21 of the affixing member engages therewith, as shown in Fig. 5, the cutting of the strip is accomplished by a shearing action commencing at the center, as shown in Figs. 5 and 11.

It is desirable in connection with a machine of this character that an accurate record be kept of all stamps fed out of the stamp box or holder and for this purpose we have provided a counter or indicator 85, of the usual or any preferred construction, which is mounted on the frame. The operating member 86 of the counter is connected by the links 87 and 88 with the stamp feeding mechanism, preferably with the sleeve 47. These operating connections should be actuated by the stamp feeding devices instead of the affixing member, as the latter may be reciprocated without necessarily discharging stamps from the machine.

A machine constructed in accordance with our invention is compact, and comprises few parts which are simple in construction and may be readily assembled.

We claim as our invention.

1. In a stamp affixer, the combination with a frame and an affixing member movable into and out of affixing position, of a liquid receptacle having a discharge chamber therein and provided with an orifice leading from said chamber, a piston reciprocating in the latter and means actuated by the affixing member for operating said piston.

2. In a stamp affixer, the combination with a frame and an affixing member movable into and out of affixing position, of a liquid receptacle provided with a discharge orifice, a wall forming a chamber in the receptacle about the inner end of the orifice, the interior of the receptacle and chamber being in communication, a piston located in the chamber and means actuated by the affixing mem-

ber for operating said piston to expel liquid from the discharge orifice.

3. In a stamp affixer, the combination with a frame and an affixing member movable into and out of affixing position, of a liquid receptacle provided with a discharge orifice, a wall arranged in the receptacle and separating a portion of the liquid therein adjacent the discharge orifice from the main body of the liquid, a piston co-operating with the wall to discharge the liquid confined by it through said orifice and means actuated by the affixing member for operating the piston.

4. In a stamp affixer, the combination with a frame and an affixing member movable into and out of affixing position, of a liquid receptacle provided with a discharge orifice located at the lower end of the side wall of the receptacle, a partition wall arranged in the latter above the orifice and near the bottom of the receptacle to separate a portion of the liquid in the vicinity of the orifice from the main body of the liquid, a piston movable relatively to the side wall of the receptacle between the bottom of the latter and said partition wall and means actuated by the affixing member for operating the piston.

5. In a stamp affixer, the combination with a reciprocating plunger and means for positioning a stamp in front of the plunger, of a liquid receptacle having a discharge orifice, means for discharging the liquid through said orifice, a spring placed under tension by the movement of the plunger and operating when released to actuate the discharging means to expel the liquid.

6. In a stamp affixer, the combination with a reciprocating plunger and means for positioning a stamp in front of the plunger, of a liquid receptacle having a discharge orifice, means for discharging the liquid through said orifice, a spring for operating said means, and members forming a latch connection between the spring and plunger for placing said spring under tension during the movement of the plunger in one direction.

7. In a stamp affixer, the combination with a reciprocating plunger and means for positioning a stamp in front of the plunger, of a liquid receptacle having a discharge orifice, means for discharging the liquid through said orifice, a spring for operating said means, and co-operating latch members on the spring and plunger respectively, for tensioning and tripping the spring during the movement of the plunger in one direction.

8. In a stamp affixer, the combination with an affixing member reciprocating in a vertical direction, and means for positioning a stamp beneath the member, of a liquid chamber having an orifice discharging in the path of said member, a piston movable horizontally in the chamber relatively to the orifice

and operating connections between the affixing member and the piston for actuating the latter to eject liquid from the orifice upon movement of the former.

- 5 9. In a stamp affixer, the combination with a frame having an apertured base and a reciprocating affixing member passing into said aperture when in affixing position, of a liquid receptacle mounted in the frame at 16 one side of the affixing member and having an orifice discharging into the path of said member, a stamp container and guideway for directing stamps into the path of the affixing member and mounted on the frame 15 at the other side of said member, means for feeding stamps along the guideway and means for ejecting liquid from the receptacle during the movement of the affixing member.
- 20 10. In a portable stamp affixer, the combination with a frame having a base provided with an aperture, a vertically reciprocating shaft guided centrally in the frame having an affixing member therein passing into said 25 aperture when in affixing position, and a liquid receptacle mounted in the frame at one side of the affixing member having a discharge orifice and provided with a piston, of a stamp container and a guideway located at the other side of the affixing member, feeding devices at one side of the affixing member coöperating with stamps in the guideway and means at the other side of said affixing member for operating the 35 piston.

11. In a stamp affixer, the combination with a frame, a liquid receptacle therein having a discharge orifice and an affixing member guided on the frame and reciprocating past 40 said receptacle, of a piston operating in the latter, a spring connected to the piston having a part adapted to be engaged by the member to place the spring under tension during the movement of the member in one 45 direction, and release said spring before the affixing member reaches the limit of its movement and means for projecting a stamp in advance of the affixing member.

12. In a stamp affixer, the combination 50 with a frame, and a movable affixing member guided on the frame, of a liquid chamber having a discharge orifice, a piston co-operating with the latter, a spring for operating it in one direction provided with a 55 part coöperating with the affixing member for placing the spring under tension and releasing it and means for positioning a stamp in the path of the affixing member.

13. In a stamp affixer, the combination 60 with a frame, and an affixing member guided on the frame and movable into and out of affixing position, of a liquid chamber having a discharge orifice, a piston co-operating with the latter and an operating 65 member connected to the piston and ar-

ranged to be set by the member during its movement into affixing position and released before said member reaches its limit of movement and devices for positioning a stamp in front of the affixing member.

14. In a stamp affixer, the combination with a frame, a liquid chamber therein having a discharge orifice and a plunger guided on the frame and reciprocating past the chamber, of a piston arranged in the 75 chamber, a leaf spring located exteriorly thereof and connected to the piston and having a projection thereon, a latch on the plunger coöperating with the projection to compress the spring during the movement of the plunger in one direction, and devices for projecting a stamp in the path of the plunger.

15. In a stamp affixer, the combination with a movable affixing member and means for positioning a stamp in front of it, of a liquid receptacle provided with an outlet orifice, a piston located within the receptacle and a yielding member holding the piston in a position to normally close the 85 orifice, said member coöperating with the affixing member to retract the piston and release it to expel liquid from the orifice.

16. In a stamp affixer, the combination with a movable affixing member and means for positioning a stamp in front of it, of a liquid receptacle, a piston chamber therein and an outlet orifice leading therefrom, a piston arranged in the chamber and normally closing the orifice and operating connections between the affixing member and piston for reciprocating the latter in its 95 chamber.

17. In a stamp affixer, the combination with a movable affixing member and a stamp 105 guide maintaining a stamp strip in flat condition throughout its length and having a throat provided with an upwardly projecting surface at its center coöperating with the extremity of the stamp strip to warp only the outermost stamp as it is projected from the guide, of means for feeding a stamp strip along the guide and over said surface into the path of the affixing member.

18. In a stamp affixer, the combination with a movable affixing member, a stamp guide and a raised surface at its extremity adapted to warp a stamp by arching it upwardly as it is discharged from the guide, of means for feeding a stamp along the 115 guide and projecting it into affixing position in front of the affixing member.

19. In a stamp affixer, the combination with a frame, a movable affixing member guided therein, a removable stamp holder 125 fitted in the frame comprising a guide having at its extremity a warping surface adapted to curve a stamp transversely as it emerges from the guide, of means for advancing stamps successively along the guide 130

into a position in front of the affixing member.

20. In a stamp affixer, the combination with a frame, a movable affixing member guided therein, a removable stamp holder secured to the frame and a stamp guide way leading therefrom having a curved extremity discharging into the path of the member, said extremity being provided with a warping surface adapted to curve a stamp transversely, of means for feeding stamps along said guide into position in front of the affixing member.

21. In a stamp affixer, the combination with a frame, a movable affixing member guided therein, a stamp container located at one side of the member and a downwardly extending stamp guide leading therefrom having a straight portion and provided at its extremity with a laterally curved end opening at one side of the path of the affixing member, of reciprocating feeding devices coöperating with the straight portion of the guide way and engaging the stamps therein for advancing and successively projecting them into a position in front of said member.

22. In a stamp affixer, the combination with a frame, a movable affixing member guided therein and provided with a cutting edge, a coöperating cutter on the frame, and a container detachably supported on the frame adapted to hold a rolled strip of stamps, of a guide way leading downwardly from the container having its open end terminating at the cutting bar and devices for advancing the strip step by step to project its extremity into the path of the affixing member.

23. In a stamp affixer, the combination with a frame, a reciprocatory stamp affixer guided therein having a shearing edge, and a coöperating cutter on the frame having an angular shaped edge, of a removable container mounted on the frame, a stamp guide way leading therefrom having its extremity located adjacent the cutter and provided with a warping surface adapted to curve a stamp transversely, and feeding devices adapted to move a stamp along the guide and project it into a position in front of the affixing member.

24. In a stamp affixer, the combination with a frame, a reciprocatory stamp affixer guided therein having a shearing edge, and a coöperating cutter on the frame having an angular shaped edge, of a container mounted on the frame adapted to hold a strip of stamps, a guide way for said strip leading downwardly from the container and having its extremity curved laterally into juxtaposition with the cutter and provided with a central portion raised above its edges and means for advancing the stamp strip by successive steps in the guide way.

25. In a stamp affixer, the combination with a frame comprising an apertured base and side pieces, a stamp affixer arranged between them and reciprocating toward and from the base and adapted to be projected through the aperture therein, of a container for a strip of stamps arranged between the side pieces and located above the affixer, a stamp guide way leading downwardly from the container and having its open end located adjacent the base of the frame and at one side of the path of the affixing member said container and guideway being removably mounted on the frame, and feeding devices for advancing a stamp strip along the guide way.

26. In a stamp affixer, the combination with a frame comprising an apertured base and side pieces, a stamp affixing member arranged between them and reciprocating toward and from the base and adapted to be projected through the aperture therein, of a container for a strip of stamps, a guideway leading therefrom, said guideway and container comprising a unit detachable from the frame and mounted thereon at one side of the affixing member, a liquid receptacle arranged between the side pieces of the frame at the other side of the affixing member, means for feeding stamps along the guideway and projecting them into the path of the affixing member from a point located at one side of said path and means for ejecting liquid from the receptacle in front of the projected stamp from a point at the opposite side of said affixing member.

27. In a stamp affixer, the combination with a container adapted to hold a strip of stamps, a guide way leading therefrom having a laterally curved extremity, and comprising a stationary portion, a movable member riding on the strip passing along the guide and adapted to be actuated to clamp said strip against the stationary part of the guide when an attempt is made to withdraw it from the outer end thereof, of means for feeding a stamp strip along the guide and an affixing member coöperating therewith.

28. In a stamp affixer, the combination with a container adapted to hold a strip of stamps, a guide way leading therefrom having a curved extremity and a yieldingly supported member resting against the curved portion of the stamp strip and adapted to be moved to clamp the strip when the free end of the latter is drawn forwardly, of means for advancing a strip along the guide way and an affixing member adapted to co-operate therewith.

29. In a stamp affixer, the combination with a holder adapted to contain a strip of stamps, a guide way leading therefrom having an extremity for projecting the end of the strip laterally and a yieldingly supported clamping member extending lengthwise

of the guide way and having a portion adapted to be moved by displacement of the strip relatively to the guide, of means engaging the strip in the guide for advancing it longitudinally therein, and an affixing member adapted to coöperate with said means and with the end of the strip.

30. In a stamp affixer, the combination with a reciprocating affixing member, a container for holding a strip of stamps and a stamp guide way leading therefrom having a curved extremity opening at one side of the path of the member, of a yieldingly supported clamping member extending along the guide way and capable of being rocked to throw one end into engagement with the guide and means operated by the movement of the affixing member in one direction for advancing the stamp strip.

31. In a stamp affixer, the combination with an affixing member, a holder adapted to contain a perforated strip of stamps and a guide way leading therefrom having a curved extremity opening at one side of the path of the member, of a projection extending into the guide way and located in a position to engage one of the perforations in the stamp strip when said strip is displaced laterally of the guide and means for advancing said strip along the guide.

32. In a stamp affixer, the combination with an affixing member, a holder adapted to contain a perforated strip of stamps and a guide way leading therefrom having a curved extremity opening at one side of the path of the member, said way comprising an outer stationary portion and an inner yielding portion, of a projection located relatively to the way and adapted to enter one of the perforations of the strip when the said strip is displaced by drawing it forwardly against the yielding portion of the way and means for advancing said strip along the guide way.

33. In a stamp affixer, the combination with an affixing member, a holder adapted to contain a perforated strip of stamps and a guide way leading therefrom having a curved extremity opening at one side of the path of the member, said way comprising a stationary back extending around the outside of the curve and a movable yieldingly supported front piece extending around the inside of the curve, of a stop finger extending into the guide and adapted to coöperate with the perforations in the strip to arrest it when said strip is displaced laterally in the guide way, and means for feeding said strip along the guide way.

34. In a stamp affixer, the combination with an affixing member, a holder adapted to contain a strip of stamps and a guide way leading therefrom, comprising a stationary back and a front piece yieldingly supported, said back and front pieces being curved at

the extremity of the guide way to direct the stamp strip across the path of the affixing member, of a stationary pin projecting into the guide way adapted to engage with the stamp strip and coöperating with said yielding front piece to prevent the withdrawal of the strip when it is displaced laterally of the guide and means for advancing the strip along the guide way.

35. In a stamp affixer, the combination with a frame, a reciprocatory affixing member guided therein, a stamp container, and a guideway leading downwardly therefrom parallel to the direction of movement of the affixing member, of feeding fingers carried by said member and extending into the guideway.

36. In a stamp affixer, the combination with a frame, a reciprocatory affixing member guided therein, and a stamp guideway having a portion extending parallel to the direction of movement of the member and a laterally curving extremity discharging into the path of said member, of a stamp feeding device mounted on the affixing member and reciprocating therewith and extending into the guideway.

37. In a stamp affixer, the combination with a frame, a reciprocatory affixing member guided therein, and a container adapted to hold a strip of stamps having a guide way leading therefrom, of a movable carriage having a feeding finger adapted to coöperate with the strip in the guide, a locking device between the affixing member and carriage, and a trip on the frame for disengaging said device.

38. In a stamp affixer, the combination with a frame, a reciprocatory affixing member guided therein, and a holder for containing a strip of stamps having a guide way leading therefrom, of a carriage guided on the member and movable independently thereof having a feeding finger coöperating with the strip in the guide way, a locking device between the carriage and member and a trip on the frame for disengaging it when the finger has advanced the strip a predetermined distance.

39. In a stamp affixer, the combination with a frame, a reciprocatory affixing member guided on the frame having a cutting edge, a cutter on the frame coöperating therewith and a holder for stamp strips having a guide way leading therefrom to the cutter, of a carriage carried on and movable independently of the affixing member having a feeding finger engaging the strip in the guide, a locking device between the latter and the carriage and a trip on the frame arranged to disengage said device previous to the engagement of the affixing member and cutter.

40. In a stamp affixer, the combination with a frame, an affixing member guided

therein comprising a reciprocatory shaft and a head, a cutter on the frame coöperating with the head and a holder for a strip of stamps having a guide way leading therefrom to the cutter, of a carriage supported on the shaft, a feeding finger on the carriage adapted to engage the stamp strip in the guide, a locking device between the carriage and affixing member, and a trip on the frame for disengaging said lock when the stamp strip has been fed forward a predetermined distance.

41. In a stamp affixer, the combination with a frame, a shaft, angular in cross section, reciprocating in the frame having a head at its lower end, a receptacle adapted to receive a strip of stamps and a guide way for the latter having its discharge end located at one side of the path of movement of the head, of a carriage guided on the shaft, a feeding finger on the carriage projecting into the guide way, a locking device on the carriage coöperating with the shaft, and a stop on the frame coöperating with the locking device to release the carriage from the shaft at a predetermined point in the movement of the latter in one direction.

42. In a stamp affixer, the combination with a frame, a removable stamp holder having a stamp guide way, stamp feeding devices comprising a reciprocatory carriage and a reciprocatory stamp affixing member, of a locking device between the carriage and member operating to lock the member in operated position when the carriage is retracted in its inoperative position.

43. In a stamp affixer, the combination with a frame, a removable stamp holder having a stamp guide way, stamp feeding devices coöperating with the guide way and comprising a reciprocatory carriage and a reciprocatory stamp affixing member, of a locking device capable of being released only when the stamp holder is displaced relatively to the frame, said device being adapted to secure the carriage and member at the limits of their movement in opposite directions.

44. In a stamp affixer, the combination with a frame, a reciprocatory affixing member guided therein, a reciprocatory carriage and a device for locking the member and carriage together at their limits of movement in opposite directions relatively to each other, of a stamp holder embodying a guide way movably mounted on the frame and normally rendering the locking device inaccessible, a feeding member on the carriage adapted to coöperate with the guide way when the carriage and member are unlocked.

45. In a stamp affixer, the combination with a frame, a reciprocatory affixing member comprising a shaft guided in the frame, a carriage mounted on the shaft and a lock-

ing device coöperating with the shaft and carriage to secure them together when the former is projected and the latter is retracted relatively to the frame, of a stamp holder embodying a guide movably mounted 70 on the frame and normally rendering said locking device inaccessible, a stamp feeding member on the carriage coöperating with the guide when the carriage is unlocked, and means operated exteriorly of the frame for 75 retaining the carriage in its inoperative position while the shaft is projected into locking position.

46. In a stamp affixer, the combination with a frame, an affixing member comprising a reciprocatory shaft guided in the frame provided with locking notches, a reciprocatory carriage and a pawl thereon adapted to engage one of the notches to cause the carriage to be reciprocated with 85 the shaft and to coöperate with the other notch to lock the shaft and carriage at the extremities of their movement in opposite directions, of a holder for stamp strips and means on the carriage for feeding stamps 90 from the holder.

47. In a stamp affixer, the combination with a frame, a reciprocatory shaft guided therein having a head and provided with spaced notches, a cutter coöperating with the 95 head and a carriage movably mounted on the shaft, of a pawl on the carriage coöperating with one of the notches to cause the carriage to move with the shaft, a stop on the frame coöperating with the pawl to disengage it when the head moves into engagement with the cutter, said pawl coöperating with the other notch to hold the shaft projected and the carriage retracted, a holder for a strip of stamps having a guide way 100 for delivering said strips into position relatively to the cutter movable relatively to the frame and normally rendering the pawl inaccessible, and feeding devices on the carriage for advancing a stamp strip along the 110 guide way.

48. In a stamp affixer, the combination with a frame, having apertured bottom and top portions, a reciprocating shaft projecting out of the top and provided at its lower end with a head operating through the bottom, a reciprocatory carriage arranged in the frame, a locking member for securing the carriage to the shaft mounted on one of said parts and coöperating with the other in 115 two positions, first to cause the carriage to reciprocate with the shaft and second to lock the shaft when the carriage is in retracted position and the shaft projected with its head located in the aperture of the frame 120 bottom, a stationary projection for tripping the member during the projecting movement of the shaft when said member is in the first mentioned position, a device operable 125 from the exterior of the frame to retain the 130

carriage and allow the shaft to be projected independently thereof, a stamp holder movable relatively to the frame and normally rendering the locking member inaccessible 5 and devices on the carriage for feeding stamps from the holder.

49. In a stamp affixer, the combination with a frame, a reciprocating affixing member, and stamp feeding mechanism, of a 10 holder adapted to contain a strip of stamps, and a stamp guide way leading therefrom, said holder and guide way being capable of displacement on the frame to permit access to the interior of the holder, and a lock for 15 retaining said parts in operative position on the frame.

50. In a stamp affixer, the combination with a frame, a reciprocating affixing member, and stamp feeding mechanism, of a 20 holder adapted to contain a strip of stamps and having a guide way, said holder having an open side and being detachably mounted on the frame in a position to prevent access to its interior and a lock for securing the 25 holder in operative position on the frame.

51. In a stamp affixer, the combination with a frame, a reciprocating affixing member, and stamp feeding mechanism, of a holder adapted to contain a strip of stamps, 30 comprising a ring having a guide way leading therefrom, said ring and guide way being detachably supported on the frame and a lock connected to said parts and comprising a bolt adapted to coöperate with the 35 frame for holding said parts in operative position thereon.

52. In a stamp affixer, the combination with a frame having side pieces, a reciprocating affixing member and stamp feeding 40 mechanism, of an open ring removably fitted between the side pieces, a stamp guide attached to the ring and means for detachably securing the ring and guide way within the frame.

45 53. In a stamp affixer, the combination with a frame having side pieces, a reciprocating affixing member and stamp feeding mechanism, of a receptacle for stamps having open sides which are closed by fitting 56 the receptacle between the side pieces of the frame, a casing connected to the receptacle and a stamp guide way located therein and locking devices arranged in said casing and comprising a bolt coöperating with the 55 frame.

54. In a stamp affixer, the combination with a reciprocating affixing member and a stamp guide way, of a stamp feeding mechanism comprising a carriage and a feeding 60 finger composed of a plurality of narrow blades each pivoted at one end to the carriage and having a shoulder, and a resilient member lying between the carriage and said shoulders.

65 55. In a stamp affixer, the combination

with a reciprocating affixer, a stamp guide way and a reciprocating carriage, of a feeding finger coöperating with the guide way composed of a plurality of narrow blades arranged side by side and pivoted to the carriage and a resilient member common to all the blades and engaging them at one side of their pivotal point and permitting them to yield independently of each other. 70

56. In a stamp affixer, the combination 75 with a reciprocating affixer, a stamp guide way and a reciprocating carriage, of a feeding finger composed of a plurality of thin, rectangular blades arranged in sidewise engagement, a pivot pin passing through them near one corner and connecting them to the carriage and a block of resilient material engaging the ends of said blades in rear of the pin. 80

57. In a stamp affixer, the combination 85 with a stamp guideway, a reciprocating affixing member, feeding mechanism coöperating with the guide way, and detachable operating connections between the member and feeding mechanism of a registering device 90 and operating connections between it and the feeding mechanism.

58. In a stamp affixer, the combination with a frame, a stamp guide way, a reciprocating affixing member having a shaft and stamp 95 feeding devices actuated by the member and comprising a sleeve carried on the shaft and a finger coöperating with the guide way to successively feed stamps therefrom, of a counter mounted on the frame and operating 100 connections between the counter and sleeve for actuating the former to record the number of stamps fed through the guide way.

59. In a stamp affixer, the combination 105 with a stamp guide way having a discharge end, a feeding member coöperating with a strip of stamps to move it longitudinally of the guide way and an affixing member, of means coöperating with the stamp strip to arrest it when said strip is drawn forwardly 110 in the guide way.

60. In a stamp affixer, the combination 115 with a stamp guide way, a movable stamp affixing member and means coöperating with a strip of stamps to push them along the guide way, of means for arresting the advancing movement of the stamp strip located at one side of the path of movement of the strip, means in the guide way for deflecting the strip so that the latter when 120 pulled in a forward direction will be drawn into engagement with the arresting member and when pushed along the guide will pass said member uninterruptedly.

61. In a stamp affixer, the combination 125 with a movable affixing member, a stamp guide way having an end located to discharge stamps at one side of the path of said member, and a feeding member adapted to push a strip of stamps along said guideway 130

and to project its extremity out of the discharge end thereof, said guide way comprising a part shaped to curve the portion of the stamp strip lying beyond the feeding member so that it will be deflected from its normal path of movement when its extremity is pulled, of an arresting member positioned relatively to the guide to engage said strip when so deflected.

62. In a stamp affixer, the combination with a movable affixing member, a stamp strip guide way arranged to discharge stamps into the path of the affixing member said guide way comprising a straight portion and a curved portion, of a feeding device coöperating with a stamp strip in the guide way to advance it therein, the curved portion of the guide way acting on said strip to curve it during its feeding movement, a retaining member yieldingly holding the stamp strip in its curved position and adapted to permit it to be deflected from the guide when the strip is drawn forwardly independently of the action of the feeding device and means arranged relatively to said guide way and adapted to engage the stamp strip to arrest its further feeding movement when said strip is deflected in the guide way.

63. In a stamp affixer, the combination with a movable affixing member, a stamp strip guide way and mechanism for advancing a stamp strip therethrough, said guide way having a portion adapted to impart a normal curve to a stamp strip and comprising means for yieldingly holding said strip in its curved position while being advanced by the feeding members and allowing it to be deflected out of its normal position when pulled along the guideway, of an arresting member arranged adjacent the guideway around one side of which the curved portion of the strip passes when advanced by the feeding member and with which the stamp strip engages when deflected.

64. In a stamp affixer, the combination with an affixing member, a stamp strip guide way having a discharge end and provided with a portion adapted to impart a continuous normal curve in a stamp strip as the latter is advanced therethrough and mechanism for feeding a strip of stamps along said guide way to eject its extremity therefrom, of an impaling pin situated relatively to the guide at the inner side of the normally curved portion, a finger yieldingly holding said curved portion out of engagement with the pin while said strip is being advanced by the feeding mechanism and adapted to move to permit said strip to engage the pin when tension is applied to the free end of the strip.

65. In a stamp affixer, the combination with a movable affixing member, a stamp strip channel and means for feeding a stamp strip therethrough, of tensioning means en-

gaging the stamp strip to control its passage through said channel, and a normally inoperative arresting element adapted to coöperate with the stamp strip when a force is applied to the stamp strip sufficient to alter the normal position of said tensioning means.

66. In a stamp affixer, the combination with a movable affixing member, a stamp strip channel and means for feeding a stamp strip therethrough, of an arresting member adapted to coöperate with a stamp strip to prevent its movement in the channel when tension is applied to move said strip along the channel by means other than the action of said feeding means.

67. In a stamp affixing machine, the combination with an affixing member and means for feeding a stamp strip forwardly to deliver successive stamps into operative position in front of the affixing member, of an arresting member adapted to coöperate with the stamp strip to stop its movement, said member being normally inoperative and adapted to be brought into action when tension is applied to move the stamp strip independently of the feeding mechanism.

68. In a stamp affixing machine, the combination with a movable affixing member and means for feeding a stamp strip progressively, of a guideway for holding a stamp strip in operative position relatively to said feeding means and directing its extremity into the path of the affixing member, said guideway being adapted to provide a free portion in the stamp strip capable of displacement relatively to the guide and means adapted to engage the stamp strip when so displaced to prevent further portions thereof from being projected from the guideway.

69. In a stamp affixing machine, the combination with a movable affixing member, a stamp strip guideway for directing the end of the strip into the path of said member having a part providing a free portion in the stamp strip which may be displaced when tension is applied to the end of the stamp strip to draw it along the guideway, of means for feeding a stamp strip progressively to successively project its end from the guideway and means adapted to coöperate with the stamp strip to prevent its end from being further advanced when the stamp strip is so displaced.

70. In a stamp affixing machine, the combination with a movable affixing member, and means for feeding a stamp strip progressively, of a guideway for holding a stamp strip in operative position relatively to said feeding means and directing its extremity into the path of the affixing member having a part providing a free portion of the stamp strip in advance of the feeding means, which may be displaced when tension is applied to the end of the strip, means adapted

to coöperate with the stamp strip when the latter is so displaced to hold it in displaced position and prevent its being projected from the guideway.

- 5 71. In a stamp affixing machine, the combination with a reciprocatory affixing member and feeding device and a stamp strip guideway for holding a stamp strip in operative position relatively to the feeding device and directing its extremity into the path of the affixing member, said guideway having a part providing a free portion of the stamp strip capable of displacement when tension is applied to the end of the strip, of means coöoperating with the free portion of the strip to hold it in normal position during the action of the feeding device, and means adapted to coöperate with said free portion of the strip when the latter is displaced and to hold it in displaced position.
- 10 72. In a stamp affixing machine, the combination with a reciprocatory affixing member and feeding device and a stamp strip guideway for holding a stamp strip in operative position relatively to the feeding device and directing its extremity into the path of the affixing member, said guideway having a part providing a free portion of the stamp strip capable of displacement relatively to the guideway when tension is applied to the end of the strip, of means adapted to coöperate with the free portion of the strip when so displaced to prevent its extremity from being projected by the action of the feeding device, and yielding members coöoperating with the stamp strip to normally hold its free portion in normal position relatively to the guide during its advancement by said feeding device.

15 73. In a stamp affixer the combination

with an affixing member, a feeding device and a stamp strip guideway comprising a backing having a laterally curved end around which the stamp strip is projected providing a portion of the stamp strip which is free to be displaced when tension is applied to said strip, of a brake shoe yieldingly supported and capable of tilting relatively to the backing and having an end arranged relatively to the curved portion of the backing adapted to be moved when the stamp strip is placed under tension to tilt its other end to clamp the stamp strip against the backing.

55 74. In a stamp affixer the combination with a frame, a reciprocatory shaft, an affixing member thereon, and a reciprocatory stamp strip feeding mechanism, of a latch member connecting the feeding mechanism and affixing member for moving the former with the latter, a stop for arresting the feeding device, said latch being adapted to yield to disconnect said parts and permit the independent movement of the affixing member.

60 75. In a stamp affixer, the combination with an affixing member and a stamp strip feeding device, said member and device being adapted to reciprocate together in the same direction, of a latch connecting them, a stop coöoperating with the feeding device to limit its movement in one direction, said latch being adapted to yield automatically to disconnect said parts and permit the continued movement of the affixing member and a spring for returning the latter to its 70 normal position with the feeding device.
